UNITED STATES PATENT OFFICE.

THOMAS McDONALD, OF YOUNGSTOWN, OHIO.

BLAST-FURNACE-CHARGING APPARATUS.

Application filed July 26, 1920. Serial No. 392,383.

To all whom it may concern:

Be it known that I, THOMAS McDONALD, a resident of Youngstown, in the county of Mahoning and State of Ohio, have invented 5 a new and useful Improvement in Blast-Furnace-Charging Apparatus, of which the following is a specification.

In my United States Patent No. 781,615 there is disclosed a blast furnace charging 10 apparatus provided with a deflector ring surrounding the lower portion of the lower charging bell and vertically movable independently thereof. The construction is such that, when the deflector ring is in a lowered 15 position, the stock or charge will be deflected towards the center of the furnace, and when such ring is in its upper position, the charge will be thrown outwardly against the wall of the furnace. The charge thus deflected 20 outwardly by this and similar types of charging apparatus rapidly abrades the furnace wall, and, to protect the refractory material thereof, it has been the practice to provide the wall with a facing ring of metal 25 wearing plates of sufficient vertical extent to cover the area struck by the outwardly deflected charge.

Although constructed of suitable thick metal, these plates nevertheless wear out 30 quite rapidly and it is necessary to renew them from time to time while the furnace remains fired. The usual practice is to dis- 35 continue the blast, charge into the furnace a considerable amount of fresh material to form a blanket over the charge already in the furnace, and then build a platform above the material on which the workmen stand while removing the worn plates and replacing them with new ones. This work is not 40 only disagreeable and uncomfortable, but also takes considerable time, because the plates are anchored to the furnace wall. Since the plates must be renewed at quite 45 frequent intervals, and it is necessary to dis- continue the blast while renewing them, considerable is added to the cost of operating the furnace.

The present invention has for its object 50 to provide means for protecting the walls of a blast furnace against abrasion by the falling stock, which means can be much more quickly and easily replaced when worn out than the former protecting means, and which, furthermore, does not need to be re- 55 newed as frequently as the former protecting means.

The invention is illustrated in the accompanying drawings, of which Fig. 1 is a partial vertical sectional view of a blast furnace top; Fig. 2 a plan view of a distributor; Fig. 3 a side view of a portion of the distributor shown in Fig. 2; and Figs. 4 and 5 vertical sectional views to enlarge scale showing alternate positions of the distributor.

The furnace and charging apparatus shown in the drawing for the purpose of illustrating the invention are substantially the same as disclosed in the above mentioned patent, but it will be understood that the invention is applicable to other forms of apparatus. The furnace is provided at its top with the usual inclined hopper 2 having an extension 3 adapted to be closed by a vertical movable bell 4, these parts being 70 of well known or of any desired forms of construction.

According to the present invention, there is provided a distributor including both an inwardly-extending deflector ring and an 80 armor extending downwardly below such ring. The distributor is preferably vertically adjustable independently of the bell for the purpose previously stated and more fully explained in the above-mentioned patent.

In the illustrative embodiment of the invention the distributor 5 is of annular form and is constructed of segments bolted to each other through outstanding flanges 6. The distributor includes a deflector ring 7 of substantially conical form and a wall-protecting armor 8 extending downwardly and at the outside of the ring 7. The armor is preferably cylindrical and formed of segments corresponding in numbers to those of the distributor, the segments being bolted together through outstanding vertical flanges 9. Furthermore, the armor is preferably detachably connected to the distributor, and for this purpose is provided with a lateral extending flange 10 through which, and a flange 11, clamping bolts 12 extend. Suitable openings 20 are provided in the wall 21 of the distributor for the passage 105 of the blast furnace gas to the down-corner.

For moving the distributor vertically, it may be provided with outwardly-projecting lugs 13 engaged by rods 14, to the upper ends of which there are suitably attached rods 15 110 extending through stuffing boxes 16. The construction of the connecting rods and the

means for moving them vertically may be the same as disclosed in the above-mentioned patent, and hence further description of them need not be made herein.

5 In Fig. 4 the distributor 5 is shown in its uppermost position. When in such position and the bell 4 lowered to permit a charge to enter the furnace, the charge is deflected outwardly against the armor 8 and hence does 10 not strike the wall of the furnace. In Fig. 6 the distributor is shown in its lowermost position, and in such position with the bell 4 lowered the charge strikes the ring 7 and is thereby deflected towards the center of 15 the furnace.

When it becomes necessary to renew the armor 8, this may be quickly done by removing the bolts 12 which clamp the armor to the distributor and also removing the 20 bolts passing through the flanges 9. This may be done in a short space of time by workmen standing upon a platform suspended from the distributor or upon a platform built upon a furnace charge in the 25 manner previously explained. By constructing the armor in segments, it may be readily placed in or taken from the furnace through the hopper opening. Thus in the practice of the invention there is eliminated the dangers involved in and the excessive amount of time required for replacing 30 wearing plates built upon the furnace wall.

According to the provisions of the patent statutes, I have described the principle and 35 operation of my invention, together with the construction which I now consider to represent the best embodiment thereof. However, I desire to have it understood that, within the scope of the appended claims, my 40 invention may be practiced by other forms of construction than that specifically shown and described.

I claim:

1. The combination with a blast furnace, 45 and a charging apparatus therefor including a hopper and a movable bell for closing the lower end of the hopper, of a vertically movable distributor outside of the hopper comprising an inwardly extending deflector ring, 50 and an armor extending downwardly below the lower edge of said ring, said armor be-

ing effective to protect the wall of the furnace against abrasion by the incoming charge in all positions of the distributor.

2. The combination with a blast furnace, 55 and a charging apparatus therefor including a hopper and a movable bell for closing the lower end of the hopper, of a vertically movable distributor outside of the hopper comprising a substantially conical inwardly extending deflector ring, and a continuous substantially cylindrical armor extending downwardly below said ring, said armor being effective to protect the wall of the furnace against abrasion by the incoming 60 charge in all positions of the distributor.

3. The combination with a blast furnace, and a charging apparatus therefor including a hopper and a movable bell for closing the lower end of the hopper, of a distributor 70 outside of the hopper vertically movable independently of the bell, said distributor comprising a substantially conical inwardly extending deflector ring and a continuous substantially cylindrical armor extending 75 downwardly below said ring and outside thereof, said armor being effective to protect the wall of the furnace against abrasion by the incoming charge in all positions of the distributor.

4. The combination with a blast furnace, and a charging apparatus therefor including a hopper and a movable bell for closing the hopper, of an inwardly extending distributor ring, and a segmental armor extending 85 downwardly below said ring and detachably connected thereto.

5. The combination with a blast furnace, and a charging apparatus therefor including a hopper and a movable bell for closing the 90 hopper, of an inwardly extending deflector ring of substantially conical form movable independently of said bell, and a segmental armor extending in cylindrical form downwardly below and outside of said ring and 95 detachably connected thereto.

In testimony, I have hereunto set my hand.

THOMAS McDONALD.
